Primary Examiner — Cathron Brooks*Assistant Examiner* — Deanna Fluegeman(74) *Attorney, Agent, or Firm* — Harness, Dickey & Pierce, P.L.C.(57) **CLAIM**

The ornamental design for a data processing system, as shown and described.

DESCRIPTION

FIG. 1 is a perspective view of a data processing system embodying our new design, taken from the front and left side; FIG. 2 is a perspective view thereof, taken from the front and right side;

FIG. 3 is a front view thereof;

FIG. 4 is a rear view thereof;

FIG. 5 is a right side view thereof;

FIG. 6 is a top view thereof; and,

FIG. 7 is a bottom view thereof.

The broken lines illustrate unclaimed environmental structure and form no part of the claimed design.
